C. BALTZELL.

CASH CARRIER.

No. 317,281.

Patented May 5, 1885.

UNITED STATES PATENT OFFICE.

CHARLES BALTZELL, OF ALTOONA, PENNSYLVANIA.

CASH-CARRIER.

SPECIFICATION forming part of Letters Patent No. 317,281, dated May 5, 1885.

Application filed March 28, 1885. (No model.)

To all whom it may concern:

Be it known that I, CHARLES BALTZELL, a citizen of the United States, residing at Altoona, in the county of Blair and State of Pennsylvania, have invented certain new and useful Improvements in Cash-Conveyers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a view in perspective. Figs. 2, 3, 4, 5, 6, 7, 8, and 9 are views in detail.

This invention, which is an improvement on a patent granted to me on the 2d day of December, 1884, and numbered 308,732, relates to that class of cash-conveyers in which balls with inclosed cash roll over elevated railways to and from the cashier's desk and by suitable devices are delivered to the cashier and forwarded by him to different parts of the room.

The invention consists in the construction and novel arrangement of parts hereinafter described, and pointed out in the appended claims.

For the sake of clearness, the devices arranged to deliver the cash-balls to the cashier's desk will be first described, and afterward the devices by which the balls are forwarded from the cashier's desk.

Referring to the accompanying drawings by letter, A designates the cashier's desk; A' A', cash-balls, and a a two parallel rods ascending vertically to the ceiling or other suitable support. The rods a form ways for the cash-carrier B, which is raised and lowered by the cords b b', pulley b², and weight b³, as in my patent hereinbefore referred to. The cord b limits the motion up and down of the carrier, and the weight b³ causes the empty carrier to ascend.

The carrier B is similar to the carrier included in my patent numbered 308,732, except that the lower clip, B', is pivoted through its center either upon the bottom or back of the carrier, in either case having vertical end openings for the passage of the rods a a. By

pivoting this clip a more free motion of the carrier in the ways is obtained, so that it will travel more easily. The upper clip, B², is 55 fixed.

C is a railway for the incoming cash-balls, descending as it approaches the cashier's desk, at a suitable distance above which it is secured. The railway C ends in the rectangular frame c on one side of the ways a. Between the standards c' c' on the side rails of the frame c is pivoted the hanging door c², as shown, one side of which faces the end of the railway C.

C' is a railway similar to the railway C, but running in the opposite direction, and having its end which faces the opposite side of the door c² secured to the side of the frame c opposite the railway C.

D is a section of railway, secured in any proper manner below the frame c at a distance therefrom a little greater than the diameter of a cash-ball. The ends of the rails of the section D face the rods a a, and are at a distance therefrom about equal to the length of the floor of the carrier. The section D descends as it approaches the rods a a, and it is essential that its end should face the same, for the reason that the cash-balls are delivered 80 therefrom onto the front end of the carrier by a device hereinafter described.

The direction in which the railways C C' approach the frame c is not essential, but the swinging door must be hung transverse to 85 their course, so that it will direct the balls which pass from the railways into the frame c down into the section D. By making the said frame sufficiently large the door c² may be made stationary, or the frame may be so constructed as to receive balls from more than two railways and deliver the same upon the section D.

E is a ball-detainer, composed of the upper arms, e e, united at their ends by the 95 curved holding-plate e' and the lower lever-arms, e² e². The said detainer is pivoted at the bends between the arms e and e² on each side upon the outer sides of the rails of the section D a short distance from its end.

e³ e³ are pins standing inward from the arms e², and arranged to impinge against the rails of the section and prevent the detainer from falling too low. The plate e' projects suffi-

ciently beyond the ends of the rails to hold the ball which rolls and rests against it upon the extreme end of the section. The ends of the lever-arms e' also project beyond the end of the section.

5 When the carrier B ascends, the outer edge of its bottom lifts the lever-arms e' , and consequently the plate e' , allowing the ball to drop off the section D and be received into the holding-opening in the bottom of the carrier. The weight of the ball then causes the carrier to descend and the detainer returns to its former position, so as to hold the next incoming ball.

The ball-delivering device described in my 15 patent numbered 308,732 may be used, if desired. In that case it is essential that the section D should run at right angles to its herein-described direction, and it may be secured to the frame c by the standards $x x$, as shown.

20 The device for forwarding the cash-balls from the cashier's desk is as follows:

$f f$ are rods rising vertically from the cashier's desk, similar to the rods $a a$ and similarly supported at their tops.

25 F is a rectangular frame traveling in the ways f by means of its side loops or notches, $f' f'$. The said frame is raised by means of the cord f^2 , attached to its top rail and passing over a pulley, f^3 , as shown. The bottom 30 rail, f^4 , of the frame serves a purpose herein-after explained.

$G G'$ are two opposite outgoing railways, which decline outward from the ways f . With the described construction the railways $G G'$ 35 and $C C'$ are to be parallel. The ways f and a must lie in planes at right angles to each other. With the construction shown in my patent referred to the ways would lie in parallel planes.

40 H is a swinging tilting yoke composed of the two outwardly-inclining arms $h h$, provided with the feet $h' h'$. The yoke H is pivoted at its bend upon the outside of one of the rods f , and swings transversely to the same at a 45 proper height above the ends of the railways $G G'$.

$I I'$ are similar vertical hooks, pivoted upon the cashier's desk at equal distances on each side of the ways f transversely thereto. The 50 said hooks are kept erect by the leaf-springs $i i'$, respectively.

J is a frame composed of the two vertical bars $j j$ and the two horizontal bars $j' j'$, which are fixed at their centers to the bars j , a little 55 above the lower end of the latter. The lower ends of the bars j pivot oppositely on the inner surfaces of the side rails of the frame F . The tops of the bars j are connected by a stay-rod.

60 K is a rod connecting the arms $y y$ of the bars j , and K' is a rod similarly connecting the arms $y' y'$ of the same.

The operation is as follows: When the frame rests upon the cashier's desk, the hooks $I I'$ 65 are engaged over the rods $K K'$, respectively.

By putting a ball, A' , into the frame J to one side of the vertical bars j —for instance, to-

ward the side of the arms y —the hook I is released from the rod K , when by lifting the frame F the engagement of the hook I' on the rod K' causes the frame J to turn to that side until the center of gravity of the ball passes the perpendicular and the arms $y' y'$ of the bars j' rest against the bottom rail, f^4 , of the frame F . The rod K' then is in position to 75 be drawn from under the hook I' , and the frames F and J rise, sustaining the ball, as shown in the drawings.

70 $L L'$ are pins standing outward from the arms $y y'$, respectively, on the same side of ways f as the tilting yoke H . The pin L , as shown in the drawings, is in position to engage against the foot h' of the arm h on that side. This action trips the frame J over to the other side and discharges the ball A' upon the railway G . The same action also swings 80 out the arm h on that side and the arm on the other side in, so that the pin L' can pass the foot of the latter arm. When the frame F is lowered, the contact with the desk brings the 85 frame J into position, and the springs $i i$ engage the hooks $I I'$ over the rods $K K'$.

Having thus described my invention, what I claim, and desire to secure, is—

1. In a cash-conveyer, the combination of 95 a cash-carrier traveling up and down on ways, a section of railway arranged to receive cash-balls from two or more railways, and a device to automatically deliver said cash-balls one by one from the said section to the cash-carrier, substantially as specified.

2. In a cash-conveyer, the combination of 100 the vertical rods $a a$ with the traveling cash-carrier B , provided with the fixed clip B^2 and pivoted clip B' , substantially as specified.

3. In a cash-conveyer, the combination of 105 the ways $a a$ and traveling cash-conveyer B with the ball-detainer E and railway-section D , arranged to receive cash-balls from two or more railways, substantially as specified.

4. In a cash-conveyer, the combination of 110 a frame traveling in vertical ways, and having pivoted upon it a cash-ball carrier adapted to receive and hold a cash-ball on either side of its center, with a tripping device hung 115 to the ways and arranged to automatically trip the ball from the carrier onto a railway on either side at will, substantially as specified.

5. In a cash-conveyer, the combination of 120 the ways $f f$, traveling frame F , and pivoted frame J , provided with the arms $y y'$ and rods $K K'$, with the hooks $I I'$ and springs $i i$, substantially as specified.

6. In a cash-conveyer, the combination of 125 the ways f , traveling frame F , and pivoted frame J , provided with the pins $L L'$, with the tripping-yoke H and railways $G G'$, substantially as specified.

In testimony whereof I affix my signature in presence of two witnesses.

CHARLES BALTZELL.
